UNITED STATES PATENT OFFICE.

HARRY LEVITEN, OF BROOKLYN, AND BENJAMIN ECKSTEIN, OF NEW YORK, N. Y.

DESIGN FOR A TOILET-ARTICLE HOLDER.

Application filed March 24, 1926. Serial No. 17,046. Term of patent 14 years.

To all whom it may concern:

Be it known that we, HARRY LEVITEN and BENJAMIN ECKSTEIN, citizens of the United States and Austria, respectively, residing, the first named in Brooklyn, county of Kings, State of New York, and the last named in New York, county of New York, State of New York, have invented a new, original, and ornamental Design for Toilet-Article Holder, of which the following is a specification, reference being had to the accompanying drawing, forming part thereof, in which the figure represents a perspective view of a toilet article holder showing our new design.

We claim:—

The ornamental design for a toilet article holder as shown.

HARRY LEVITEN.
BENJAMIN ECKSTEIN.
